UNITED STATES PATENT OFFICE.

WILLIAM KOECK AND JOSEPH KOECK, OF OSHKOSH, WISCONSIN.

JACK.

Application filed March 16, 1920. Serial No. 366,255.

To all whom it may concern:

Be it known that we, WILLIAM KOECK and JOSEPH KOECK, citizens of the United States, and residents of Oshkosh, in the county of Winnebago and State of Wisconsin, have invented new and useful Improvements in Jacks, of which the following is a description, reference being had to the accompanying drawings, which are a part of this specification.

The present invention relates to certain new and useful improvements in lifting jacks.

One object of the present invention is to provide a lifting jack so constructed that the operator may position the same beneath a car and raise or lower same without kneeling to operate the releasing mechanism and thus proving a great convenience over the jacks now in every day use.

Another object of this invention is to provide a jack in which the lifting or elevating member may be raised its entire limit of movement by one movement of the operating handle, if desired.

A further object of our invention is to provide a jack of the class described utilizing means for obtaining the desired leverage and provided with means for locking the elevating member in any one of several positions.

A still further object of the present invention is to provide a jack of the class described which will be of comparatively light construction but readily capable of supporting heavy weights, and which will have a powerful leverage and will perform its functions in an efficient manner.

With the above and other objects in view which will appear as the description proceeds, our invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings we have illustrated one complete example of the physical embodiment of our invention constructed according to the best mode we have so far devised for the practical application of the principles thereof, and in which:

Figure 1 is a side view of our improved jack with the elevating member in its fully

extended position, parts being broken away and in section to more clearly illustrate structural details.

Figure 2 is a side elevational view thereof with the elevating member in its lowermost position.

Figure 3 is a sectional view taken through our improved jack on the line 3—3 of Figure 2.

Figure 4 is a view part in section and part in elevation taken on the plane indicated by the line 4—4 of Figure 5, the elevating member being depicted in an intermediate position, and

Figure 5 is a sectional view taken through our improved jack on the line 5—5 of Figure 4.

Referring now more particularly to the drawings, the numeral 10 designates a body portion or supporting base from which extends a tubular or channeled standard 11 in which is slidably mounted an elevating member including two complementary strips or the like 12. The members 12 are secured together at their upper ends and retained in spaced relation by means of a cap 13, shaped to engage with various shaped articles to be lifted.

The lower ends of the members 12 are retained in spaced relation by means of two complementary discs or wheels 14 journally mounted therebetween adjacent their lower ends by means of a stub shaft or journal pin 15. The stub shaft 15 has its ends slidably mounted within elongated apertures 16 and 17 formed in the standards 11 and the members 12 respectively, which construction permits the vertical movement of the elevating member within said standard, such movement being equal to the combined length of the apertures 16 and 17.

The discs 14 are maintained in spaced relation as depicted in Figures 3 and 5 by means of toggle links 18 and 19 and an operating lever receiving socket 20. The lever receiving socket 20 has its inner end 21 flattened to a thickness equal to the distance between the discs 14 and is provided with an elongated slot 22 through which the pin 15 passes. The toggle links 18 and 19 are of a thickness substantially the same as the inner flattened ends of the socket member 20, and the toggle link 18 has its lower end pivotally secured between the discs 14 adjacent the periphery thereof by a pin 23 and has its upper end pivotally secured as at 24 to the cap 13.

The toggle link 19 has its upper end pivotally secured between the discs 14 by a pin 25 positioned diametrically opposite the pin 23, and has its lower end pivotally secured as at 5 26 to the base 10. This construction extends or elevates the cap 13 upon rotation of the discs 14 on their pivots 15 to bring the pins 23 and 25 in substantially vertical alignment, see Figure 1.

10 The jack is maintained in its extended position by a slight movement of the discs 14 to bring the pins 23 and 25 beyond an imaginary line drawn perpendicularly through the center of the pin 15, and the 15 link 19 will abut a projection 27 carried by the standard 11. When the members 12 are completely telescoped within the standard 11 their lowermost ends engage or 20 impinge against the base 10 and apertures 28 formed therein permit the same to pass over the pin 26.

The discs 14 are rotated by the handle 20 which is provided with two opposed lugs 29 engageable within complementary opposed openings 30 formed in the discs 14. 25 The openings 30 are shaped to provide shoulders or locking recesses 31 in which the projections 29 are seated when it is desired to elevate the cap 13 its entire limit 30 of movement upon one movement of the hand. In the event that the automobile bumper or some other obstacle prevents the 35 positioning of the handle 20 to engage the recesses 31, the projections 29 are engaged in lower recesses 32 and the discs given a partial rotation and held in such position by means to be later described, until the lugs 29 can be engaged in recesses 33 slightly above the recesses 32 and permit the 40 continued movement or rotation of the discs to fully elevate the cap 13 and pass the pins 23 and 25 beyond center as before described.

The means for maintaining the discs in 45 such partial rotated position includes a pawl or latch member 34 having its lower end pivoted as at 35 to the base and its upper end engageable with the periphery of the discs by means of an extensile spring 36 50 abutting the standard 11 and a lip 37 formed on the pawl 34 below its pivot.

The discs 14 are provided in their periphery with aligned locking recesses 38 adapted to receive the upper end of the pawl 34 and 55 be thus held from counter-clockwise rotation with respect to Figures 1 and 4 beyond said pawl unless the pawl is urged outwardly against the action of its spring 36.

Thus with this construction, when the 60 projections 28 are engaged in the recesses 32 and the cap 13 elevated approximately one-half its normal limit of movement, the pawl 34 will engage within the recesses 38 and lock the same in such position until the 65 projections 29 can be engaged in the recesses

33 and the discs 14 rotated to bring the pins 23 and 25 beyond center as before described.

The return of the jack to normal position is accomplished by engaging the projections 29 in the recesses 31 and lifting upon the 70 handle to bring the pins 23 and 25 back over the center when the weight of the article upon the cap 13 will tend to return the same to such normal position, and the pawl 34 will engage within the notches 38 when the 75 same has been returned part way. The lugs 29 are then engaged in the recesses 33 and the extreme inner end of the handle 20 will engage a member 39 carried by the pawl 34 and thus move the member 34 from engagement with the notches 38 and permitting the 80 return of the parts to normal position as will be readily obvious.

From the foregoing description taken in connection with the accompanying drawings 85 it will be at once apparent to those skilled in the art to which an invention of this character appertains that we have provided an improved lifting jack having what may be termed a variable fulcrum connected 90 with the elevating member and the base by means of a double toggle connection.

What we claim as our invention is:

1. A jack comprising a body portion, an elevating member carried thereby, a fulcrum, a toggle connection between the fulcrum and the elevating member for operating the same, means for releasably securing said member in fully elevated position, and means independent of said first mentioned 100 means for releasably securing said member in an intermediate position.

2. A jack comprising a body portion, an elevating member carried thereby, a disc movably carried by the body portion, a link 105 having one end pivoted to the elevating member and its other end pivoted to said disc spaced from the center thereof, means for rotating said disc to elevate and lower said member, means engageable with the 110 periphery of said disc for releasably securing the elevating member in adjusted position, and means connecting said disc and body and co-operating with said link for securing said elevating member in elevated 115 position.

3. A jack comprising a body portion, an elevating member carried thereby, a disc revolvably carried by the body portion, a wrist pin carried by said disc, a link having 120 one end pivoted to the elevating member and its other end pivoted to said wrist pin, means for rotating the disc to elevate and lower said member, and means for releasably securing the elevating member in any 125 one of several positions.

4. A jack comprising a body portion, an elevating member carried thereby, a disc revolvably carried by the body portion, a wrist pin carried by said disc, a link having 130

one end pivoted to the elevating member and its other end pivoted to said wrist pin, means for rotating the disc to elevate and lower said member, and means engageable 5 with said disc to releasably secure the elevating member in any one of several positions.

5. A jack comprising a body portion, an elevating member carried thereby, a double 10 toggle connection between said member and body portion, the centers of said toggle connection being movable a slight distance beyond an imaginary perpendicular line to releasably secure said member in fully elevated position, and means for securing said member in an intermediate position.

6. A jack comprising a body portion, an elevating member carried thereby, a fulcrum, a toggle connection between the body 20 portion and elevating member and said fulcrum and operable to raise and lower the elevating member, means for releasably securing said member in fully elevated position, and means independent of said first 25 mentioned means for releasably securing said member in an intermediate position.

7. A jack comprising a body portion, an elevating member carried thereby slotted rotatable discs forming a readily variable 30 fulcrum, and a double toggle connection between the body portion and elevating member and said fulcrum.

8. A jack comprising a body portion, an elevating member vertically slidably mounted 35 therein, a vertically movably pivoted disc, a toggle link having one end pivoted to said disc off the center thereof and its other end pivoted to said elevating member, a second toggle link having its upper end 40 pivoted to said disc diametrically opposite to the pivot of said other toggle link and its other end pivoted to said body portion, and means for rotating said disc to bring the pivots of said toggle links connected with 45 said discs in substantially vertical alignment to elevate said member.

9. A jack comprising a body portion, an elevating member vertically slidably mounted 50 therein, a vertically movably pivoted disc, a toggle link having one end pivoted to said disc off the center thereof and its other end pivoted to said elevating member, a second toggle link having its upper end 55 pivoted to said disc diametrically opposite to the pivot of said other toggle link and its other end pivoted to said body portion, and means for rotating said disc to bring the pivots of said toggle links connected with 60 said discs in substantially vertical alignment to elevate said member, said pivots being movable slidably beyond an imaginary line drawn perpendicularly

through the center of said disc to releasably lock the elevated member in extended position.

65

10. A jack comprising a body portion, an elevating member vertically slidably mounted therein, a vertically movable pivoted disc, a toggle link having one end pivoted to said disc off the center thereof and its 70 other end pivoted to said elevating member, a second toggle link having its other end pivoted to said disc diametrically opposite to the pivot of said first mentioned link and its other end pivoted to said body portion, 75 means for rotating said disc to bring the pivots of said toggle links connected therewith in substantially vertical alignment to elevate said member, said pivots being movable slightly beyond an imaginary line 80 drawn perpendicular through the center of said disc, and means engageable with one of said links when said pivots are passed beyond said imaginary line to prevent the accidental descent of the elevating member. 85

11. A jack comprising a body portion, an elevating member vertically slidably mounted therein, a vertically movable pivoted disc, a toggle link having one end pivoted to said disc off the center thereof and its other end 90 pivoted to said elevating member, a second toggle link having its other end pivoted to said disc diametrically opposite to the pivot of said first mentioned link and its other end pivoted to said body portion, 95 means for rotating said disc to bring the pivots of said toggle links connected therewith in substantially vertical alignment to elevate said member, said pivots being movable slightly beyond an imaginary line 100 drawn perpendicular through the center of said disc to releasably secure the elevating member in fully elevated position, and a pawl carried by said body member and engageable in a recess in said disc to releasably 105 secure said elevating member in an elevated position.

12. A jack comprising a body portion, an elevating member carried thereby, a disc rotatably mounted in the body portion, connections between said disc and elevating member whereby a rotation of said disc will raise and lower the same, and means for rotating said disc including a lever having one end pivotally connected with said member 110 and provided with an intermediate projection selectively engageable in recesses in said disc spaced different distances from the center thereof whereby the leverage of said lever may be adjusted. 115

In testimony whereof, we affix our signatures.

WILLIAM KOECK.
JOSEPH KOECK.
